HAND BOTTLE CAPPER

Herman A. Harder, Milwaukee, Wis.

Application October 15, 1942, Serial No. 462,147

8 Claims. (Cl. 226—92)

This invention relates to bottle capping apparatus and refers particularly to a portable hand capper especially adapted for use in dairies for capping odd sized bottles of which the quantity handled is not sufficient to warrant provision for automatic capping.

One of the objects of this invention is to provide a hand capper of the character described which is light and although fully self contained, that is, carries its own cap magazine, can be readily handled and manipulated.

Another object of this invention is to provide a capper of the character described wherein the handles by which it is carried and manipulated are substantially symmetrically arranged at opposite sides of the axis of the cap applying plunger so that the capping pressure is centered over the plunger.

Another object of this invention is to provide a hand bottle capper wherein the feeding of the caps from the magazine into position for application to the bottles is effected by merely pivotally moving one of a pair of pivotally connected handles both of which are connected to the plunger to apply the capping pressure thereto.

Still another object of this invention is to provide a hand bottle capper which is inexpensive, simple in design, and sufficiently rugged to withstand the rough handling to which a device of this character would be subjected.

With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate one complete example of the physical embodiment of the invention constructed according to the best mode so far devised for the practical application of the principles thereof, and in which:

Figure 1 is a perspective view of a bottle capper constructed in accordance with this invention and illustrating its manner of use;

Figure 2 is a top plan view of the capper with part of its handles broken away;

Figure 3 is a longitudinal sectional view through Figure 2 substantially on the plane of the line 3—3, and showing the plunger raised and a cap in position thereunder;

Figure 4 is a view similar to Figure 3 but show-

ing the plunger depressed and the cap applied to the bottle; and

Figure 5 is a longitudinal sectional view taken through Figure 2 on the plane of the line 5—5.

Referring now particularly to the accompanying drawings, in which like numerals indicate like parts, the numeral 5 designates the base of the capper which is substantially a flat wall having a round hole 6 therethrough and a cap magazine 7 mounted thereon alongside the hole 6. The hole 6 forms a cap guideway through which caps are individually pushed for application to the bottles.

Three downwardly projecting lugs 8 on the underside of the base embrace the mouths of the bottles to center the base thereon with its hole 6 coaxial with the bottle mouth. It is, of course, to be understood that the capper is designed for only one cap size.

Reciprocally mounted above the hole 6 and coaxially therewith is a plunger 9 the stem 10 of which slides in the bore of the vertical hub 11 connected by spider arms 12 with the base. This plunger support may be made separately of the base and screwed thereto or it may be cast integrally with the base. In any event, the plunger 9 is guided thereby for reciprocation coaxially of the cap guideway provided by the hole 6, and to prevent rotation of the plunger for a purpose to be hereinafter described, a pin 13 fixed therein extends upwardly from the plunger to be slidably received in a bore 14 in one of the spider arms 12.

The upper end of the plunger stem 10 which projects above the hub 11 has two handles 15 and 16 connected therewith and extending substantially in opposite directions so that downward force applied to the handles is centered over the plunger.

The handle 15 is pinned to the plunger stem as at 17 and as the plunger is restrained against rotation it follows that this handle is held against turning about the plunger axis. The handle 16, however, is free to pivot about the plunger axis an amount determined by the adjustment of the two set screws 18 and 19. These screws are threaded in arms 20 which project laterally from the pivoted end of the handle 16, and are engageable with a shoulder 21 on the handle 15.

The pivotal movement thus provided for the handle 16 is utilized to successively slide the lowermost cap in the magazine 7 into the cap guideway 6 under the plunger. To this end the handle 16 has a lever arm 22 formed integrally therewith and extending downwardly and out-

wardly from its mounted end portion. A vertical pin or stud 23 carried by the extremity of this lever 22 is received in an elongated slot 24 in an arm 25 mounted to swing about a vertical axis. Thus, by pivotal movement of the handle 16 the arm 25 may be oscillated about the axis of its mounting.

The mounting of the arm or lever 25, as best illustrated in Figure 4, consists of a stud or pin 26 anchored in the base and projecting upwardly therefrom. A boss 27 on the underside of the base provides increased length for the bore in which the pin 26 is stepped. Freely rotatably mounted on the pin or stud 26 is a sleeve 28 the upper end of which is reduced in diameter and has the lever arm 25 mounted thereon.

The angular position of the arm 25 with respect to the sleeve 28 must be adjustable and hence, set screws 30 lock the lever arm to the sleeve 28.

The lower end of the sleeve 28 has a push-off arm 31 fixed thereto by a headed drive screw 32. The push-off arm is a thin, flat, curved member adapted to swing edgewise across the bottom of the cap magazine to slide the lowermost cap in the magazine into the guideway 6. The side of the cap magazine facing the mounting of the push-off arm 31 is spaced from the base to accommodate the arm and a similar space provides the necessary discharge port 33 through which the caps are singly slid into the hole 6.

To properly guide the caps as they are fed through the discharge port 33, the top of the base is milled to provide a slideway 34 the side edges of which are tangent with the walls of the bore or hole 6.

In use it is, of course, necessary that a cap be slid from the magazine and deposited under the plunger so that downward pressure on the plunger may press the cap onto the mouth of the bottle. This, as already pointed out, is accomplished by swinging the handle 16 about its pivotal connection with the plunger stem and with respect to the other handle 15 to actuate the push-off arm 31.

The throw of the push-off arm 31 must be accurately adjusted so that in its retracted position, shown in dotted lines in Figure 2 and at which time the handle 16 is swung to the rear or toward the magazine, it shall clear the full diameter of the caps and allow the pile to drop down onto the bottom of the magazine, while at the end of its feeding stroke the arm 31 should stop in the full line position shown in Figure 2, at which time it has just pushed a cap into the hole 6.

Having properly set the angular relationship between the push-off arm 31 and the lever 25 by means of the set screws 30, the final adjustment for the throw of the push-off arm 31 is effected by the set screws 18 and 19.

Naturally, it is undesirable to permit feeding a cap from the magazine when the plunger is lowered and to this end the top of the plunger is formed with an abutment 35 which, in the lowered position of the plunger shown in Figures 4 and 5, forms an obstruction lying across the discharge port of the mechanism. To maintain this obstruction properly aligned with the discharge port is the function of the pin 13 which slides in the bore 14 and thus holds the plunger against turning.

An advantage of the capper of this invention results from the fact that the handles are attached to the plunger. Hence, when the capper is supported by the handles the plunger is automatically in its elevated position, the weight of

the capper being then supported by the top of the plunger coming against the underside of the spider arms 12. In this position the pivoted handle 16 may be readily manipulated to slide a cap into position under the plunger. Hence the simple act of lifting the capper off the bottle at the completion of its capping operation automatically "sets the stage" for the next cycle.

From the foregoing description, taken in connection with the accompanying drawings, it will be readily apparent to those skilled in the art, that this invention provides an exceedingly handy bottle capper which is admirably suited for short runs of special sized bottles as, for instance, the type used by dairies for cottage cheese.

What I claim as my invention is:

1. A hand bottle capper comprising: a base having an apertured portion adapted to fit the mouth of a bottle; a plunger reciprocally mounted on the base and projectible through the aperture therein; a pair of handles attached to the plunger and extending to opposite sides of its axis so that an operator holding the capper by said two handles may readily apply downward force on the plunger to press a cap through the aperture in the base and onto the bottle; a pivotal connection between said handles whereby one of the handles is free to swing in a plane parallel to the base; a cap magazine on the base alongside its apertured portion; and a pushoff arm operatively connected with said first designated handle and operable by pivotal movement thereof relative to the other of said handles to slide the lowermost cap in the magazine under the plunger; said positioning of the cap under the plunger requiring the plunger to be in its elevated position with respect to the base and said relationship being automatically secured by virtue of the weight of the capper being supported from the plunger when the capper is lifted off a bottle whereby positioning of the caps under the plunger may be effected while the operator is moving the capper from one bottle to another.

2. A hand bottle capper of the character described comprising: a base having a hole therethrough providing a cap guideway through which caps may be pushed for application onto bottles; means for centering the base on the mouth of a bottle with its cap guideway in alignment therewith; a plunger reciprocally mounted on the base in line with the cap guideway for pushing a cap through the guideway and onto the mouth of a bottle; a handle fixed to the plunger by which it may be reciprocated with respect to the base; a cap magazine on the base alongside said cap guideway and having a lateral discharge port through which caps may be fed to the cap guideway; means for pushing the lowermost cap in the magazine through said discharge port; and a second handle pivotally carried by the plunger so as to be rotatable about the axis of the plunger, said second handle being operatively connected with said last named means for actuating the same, said handles extending substantially in opposite directions from the axis of the plunger so that downward force applied thereon is substantially centered over the plunger, and the weight of the capper being suspended from the plunger when the capper is lifted off a bottle so that feeding of the caps from the magazine under the plunger may be effected while the capper is being moved from one bottle to the other.

3. A hand bottle capper of the character described comprising: a base having a hole therethrough providing a cap guideway; means on the

bottom of the base for embracing the top of a bottle to center the cap guideway over the mouth of the bottle; a plunger reciprocally mounted on the base in line with the cap guideway and operable to push a cap through the guideway onto the mouth of a bottle; a cap magazine carried by the base; a discharge port leading from the magazine to the cap guideway through which the lowermost cap in the magazine may be pushed into the cap guideway; oppositely extending relatively movable handles one of which is connected to the plunger in a manner such that the other handle is constrained to motion in a plane parallel with the base; and means operatively connected with the other handle and movable thereby for sliding the lowermost cap in the magazine through the discharge port and into the cap guideway, such feeding of caps into the cap guideway necessitating the plunger being elevated with respect to the base and the reciprocal mounting of the plunger in the base allowing the base to automatically assume said relationship upon lifting the capper off a bottle so that the cap feeding may be effected before the capper is again in position to apply a cap to a bottle.

4. A hand capper of the character described comprising: a base; a plunger mounted on the base for reciprocation between defined limits; a cap magazine mounted on the base; a discharge port leading from the magazine and positioned to guide caps into the path of the plunger; mechanism for feeding caps singly from the magazine through said port and into the path of the plunger; and a handle structure fixed to the plunger by which downward pressure may be applied to the plunger and by which the entire capper is supported with the weight of the capper suspended on the plunger to automatically bring the plunger to its raised position, said handle structure including a part supported from the plunger for oscillatory motion relative to the plunger; and means connecting said part of the handle structure with the mechanism for feeding off the caps so that cap feed-off from the magazine is controlled by oscillation of said handle structure part independently of plunger motion.

5. A hand bottle capper comprising: a reciprocal plunger for pressing caps individually onto the mouths of bottles; means for centering the plunger over the mouth of a bottle; a cap magazine; means for guiding caps from the magazine to a capping position under the plunger; a pair of handles connected to the plunger, one of which is secured against movement with respect to the plunger and the other having a degree of swinging movement about an axis parallel with the plunger motion; mechanism operable by swinging movement of said movable handle for individually feeding caps from the magazine to the capping position under the plunger; and means for preventing the feeding of caps from the magazine when the plunger is in its depressed position but not when it is elevated, the entire capper structure other than the plung-

er and handles being supported from the plunger when the capper is lifted off a bottle so that the act of lifting the capper off a bottle automatically places the plunger in its elevated position and disables the feed preventing means to allow another cap to be fed from the magazine as soon as the capper is lifted off a bottle.

6. In a hand bottle capper: a base having a hole through which caps may be fed for application to the mouths of bottles; a plunger; means on the base guiding the plunger for reciprocatory motion toward and from the hole in the base and by which the base and all structure thereon is suspended from the plunger when the capper is not seated on a bottle; a cap magazine on the base; a discharge port leading from the magazine and having means for guiding caps to the hole; a pushoff arm mounted on the base to swing across the bottom of the magazine and feed caps singly from the magazine and into said hole; means for actuating the pushoff arm; a handle pivotally mounted from the plunger to swing about an axis substantially normal to the swinging motion of the pushoff arm and by which pressure may be applied on the plunger to move the same toward the hole in the base; and levers fixed with respect to the pushoff arm and the handle and connected by a pin and slot so that pivotal movement of the handle swings the pushoff arm between defined limits.

7. In a hand capper of the character described: a base having a hole therethrough; a plunger guideway mounted on the base above said hole; a plunger in the hole and having a stem reciprocal in said guideway; handle means fastened to the stem and by which reciprocation of the plunger may be effected, the weight of the base and all structure thereon being suspended from the plunger when the capper is picked up by its handle means, said handle means including a part movable relatively to the stem in a plane parallel to the base; and cap feeding means operable by movement of said handle part relatively to the stem for feeding caps singly into said hole and under the plunger.

8. In a hand bottle capper of the character described: a base; a cap magazine carried by the base; a pair of hingedly connected handles; a plunger mounted for reciprocation on the base alongside the cap magazine and having a stem attached to said handles in such a way that one of the handles is fixed with respect to the plunger while the other is free to swing between limits about an axis parallel with the line of reciprocation of the plunger, the weight of the base and all structure thereon being suspended from the plunger when the capper is lifted by its handles; and means actuated by swinging motion of said first designated handle relative to the other handle for carrying bottle caps from the magazine along the base to a position under the plunger,

HERMAN A. HARDER.
